JACOB SAMUELS, OF NEW YORK, N. Y.

STOCKING ATTACHMENT.

1,123,015.

Specification of Letters Patent. Patented Dec. 29, 1914.

Application filed September 3, 1914. Serial No. 859,978.

To all whom it may concern:

Be it known that I, JACOB SAMUELS, a citizen of the United States, and a resident of the city of New York, borough of the Bronx, in the county of the Bronx and State of New York, have invented a new and Improved Stocking Attachment, of which the following is a full, clear, and exact description.

10 This invention relates to wearing apparel, and has particular reference to stockings of the type adapted especially for ladies; although the improvement is adapted also for men's or children's stockings.

15 Among the objects of the invention is to simplify and improve the reinforcing devices for the upper end of the stocking for coöperation with the hose supporter, having reference particularly to the neatness of appearance and the provision of ample strength without detracting in any manner from the circumferential elasticity of the stocking.

20 The foregoing and other objects of the invention will hereinafter be more fully described and claimed and illustrated in the drawings forming a part of this specification in which like characters of reference indicate corresponding parts in all the views, 30 and in which—

25 Figure 1 is a perspective view of the upper end of a stocking having my improvement formed therein; and Fig. 2 is a sectional detail on the line 2—2 of Fig. 1.

35 Referring more particularly to the drawings I show, by way of illustration of a preferred adaptation of this improvement, a stocking 10 having a hem 11 at its upper end. The hem, as usual, is formed by folding over a portion of the stocking leg and securing the edge thereof by any suitable manner, and the material of which the stocking is made may be modified irrespective of the specific improvement but comprises, as 45 usual, a flexible fabric material or one which is adapted to stretch circumferentially.

40 Since stockings are ordinarily supported by metallic attachments which interlock in various ways with the hem or upper end portion of the stocking, it has become necessary, or at least essential, that reinforcement means of some character be used in connection with the stocking to prevent pulling, tearing, or running of the stocking due to 50 the strain thereon of the supporters. Vari-

ous means have been proposed to provide the necessary reinforcements, but I have found that practically all of these provisions, while more or less answering the demand for strength or protection of the stocking, are unsatisfactory, either because they are unsightly or because they interfere to a considerable extent with the elasticity of the stocking circumferentially. In other words, it is necessary in a satisfactory attachment of this nature for the connection between the reinforcement and the stocking to be firm and strong vertically, and for the connection between the reinforcement and the stocking to have considerable extent up and down.

55 To meet the requirements above indicated, I provide a short piece of tape 12 or other tough, flexible and nonelastic material which I introduce within the hem of the stocking or between the two plies of material forming the hem, as indicated best in Fig. 2. This reinforcement, which may be referred to for simplicity hereinafter as "tape," may be of any suitable length, but is shown herein as being substantially equal to the vertical width of the hem and may be of a width of about one-half inch, more or less, in practice. Stockings being commonly manufactured in flat form, the operation is begun at the toe, and when it reaches a distance far enough to form the hem, the hem is turned down and secured along its edge to the body of the stocking while yet in flat form. Subsequently the stocking is formed into tubular form with the folded portion of the hem on the inside. In order to manufacture these stockings I introduce the short pieces of tape into the hem between the two plies thereof after the hem is formed, but while the stocking is still flat, such tape pieces being introduced at the ends of the hem and passed as far along the hem as desired. The tape 12 is secured in place within the hem by a single vertical row of stitches 13 extending from one end of the tape to the other along its middle portion. The side edges of the tape are not secured by any means to the stocking, but simply lie in position flatly between the two portions of the hem, being held in such position by the stitches 13 and the stocking members. I have found in practice that there is no tendency for this tape to curl up or pull or otherwise assume any other form than that indicated. The 105 110 115

stitches 13 extend through both plies of the hem 11 as well as through the tape, and hence the hem portion of the stocking adjacent the tape is maintained by the stitches 13 in a firm strong condition. A stocking supporter, therefore, connected to the stocking through any one of a plurality of holes 14 will not tear nor damage the stocking, because the force thereon will be resisted or borne by the entire reinforcement tape as applied through a considerable length of the stocking vertically by the stitches 13. The holes 14 are formed preferably through the entire hem and the tape, and the edges thereof are preferably worked through all three of the parts, the buttonhole working constituting further strengthening means for the central part of the tape attachment.

The structure herein described including a piece of tape for the reinforcement makes it possible to form a hole 14 of considerable width, if desired, for the easy admission of the stocking supporter. The working of the buttonhole through both plies of the hem and through the uncut portion of the tape makes a strong attachment and does not interfere with the circumferential elasticity of the stocking top.

While I indicate in the drawings a stocking having but one reinforcement tape, it will be obvious that any number may be employed in the same stocking, and hence I do not wish to be limited in this or any other particular as to the details of the de-

vice except as may be required by the state 35 of the art.

I claim:

1. In a stocking attachment, the combination with the upper end of a stocking having a hem, of a strip of flexible material arranged entirely within said hem between the plies of material forming the same, said strip of material being non-elastic vertically, a row of stitches extending vertically from one edge of the strip to the other, securing it to the stocking hem, and a hole formed through the strip of material and hem plies in the line of said stitches, substantially as set forth.

2. In a stocking attachment, the combination with the upper end of a stocking having a hem, of a strip of tape arranged vertically entirely within said hem between the plies of the material forming the same, a single row of stitches extending vertically from one end of the tape to the other along its center, securing it to the stocking, and a hole formed through the tape and hem plies in the line of said stitches, substantially as set forth.

In testimony whereof I have signed my name to this specification in the presence of two subscribing witnesses.

JACOB SAMUELS.
